UNITED STATES PATENT OFFICE.

FRANK A. WILMOT, OF BRIDGEPORT, CONNECTICUT, ASSIGNOR TO THE WILMOT & HOBBS MANUFACTURING COMPANY, OF SAME PLACE.

DESIGN FOR A RIM FOR PNEUMATIC VEHICLE-WHEELS.

SPECIFICATION forming part of Design No. 33,834, dated January 1, 1901.

Application filed October 25, 1900. Serial No. 34,395. Term of patent 14 years.

To all whom it may concern:

Be it known that I, FRANK A. WILMOT, a citizen of the United States, residing at Bridgeport, county of Fairfield, State of Connecticut, have invented and produced a new and original Design for a Rim for Pneumatic Vehicle-Wheels, of which the following is a specification, reference being had to the accompanying drawings, forming part thereof.

10 In the drawings, Figure 1 represents a side elevation of my new and original rim for pneumatic vehicle-wheels; and Fig. 2 represents a cross-section of the same, showing a portion of the rim in perspective.

15 The leading or material feature of my design consists of a rim of the shape substantially as shown in the drawings and including a central shallow and slightly-rounded groove or depression, the portions of the rim each

20 side of said groove or depression being similarly grooved, but forming segments of a smaller circle than that of the said groove,

the extreme outer edges of the side portions being flared, and the groove or depression being of less width than either of said side portions, the central groove or depression and the two side portions giving a three-band effect, as shown in Fig. 2.

In the drawings, A represents the shallow or relatively narrow groove. B represents the curved side portions, and the outwardly-flared edges are represented at C.

Having thus described my invention, what I claim as new, and desire to secure by Letters Patent, is—

35 The design for a rim for pneumatic vehicle-wheels, substantially as herein shown and described.

In testimony whereof I affix my signature in presence of two witnesses.

FRANK A. WILMOT.
